UNITED STATES PATENT OFFICE.

JOHN CHRISTIANSEN, OF PLATTSMOUTH, NEBRASKA.

IMPROVEMENT IN BALANCED SLIDE-VALVES.

Specification forming part of Letters Patent No. 122,438, dated January 2, 1872.

To all whom it may concern:

Be it known that I, JOHN CHRISTIANSEN, of Plattsmouth, in the county of Cass and State of Nebraska, have invented a new and Improved Balance Slide-Valve; and I do hereby declare the following to be a full, clear, and exact description thereof, which will enable those skilled in the art to make and use the same, reference being had to the accompanying drawing forming part of this specification, in which drawing—

Figure 1 represents a longitudinal vertical section of this invention. Fig. 2 is a transverse vertical section of the same in the plane $x x$ of Fig. 1. Fig. 3 is a detached plan of one of the split-rings. Figs. 4 and 5 are modifications of my invention.

Similar letters indicate corresponding parts. This invention consists in the arrangement of a series of disk-springs in combination with the slide-valve of a steam-engine, which is connected to said spring or springs with or without an intermediate lever in such a manner that when steam is admitted to the valve-chest the disk-springs are compressed, and by this compression the pressure of the steam on the back of the valve is counteracted, and consequently the valve is balanced. The connections between the balance-rod and the steam-chest at one end of said rod are formed by knife-edge bearings, so as to render the motion of the valve as unobstructed as possible. The disk-valves are secured together by conical screw-plugs, split-rings, and thimbles, whereby a simple and durable connection is produced and the steam is effectually prevented from entering into the hollow disk-springs.

In the drawing, the letter A designates the steam-chest of a steam-cylinder, and in this steam-chest works the slide-valve B in the usual manner, said valve being connected to its rod C, so that it can rise and fall within certain limits. In the back of the valve are secured two knife-edged bearings, $a a$, which catch in the eyes of a yoke, b , and this yoke connects, by a series of hollow disk-springs, D, with a rod, E, that is suspended from a knife-edge bearing, a' , secured in the top of the steam-chest, as shown in the drawing. The disk-springs are made of sheet-copper or other

sheet metal, each of two parts, which are bound together at their edges, and strengthened by rings d of metal wire. The inner edges of the disk-springs are turned up in opposite directions to form flanges e , and the outside flanges of the end springs are clamped between rings f and thimbles g , said rings being provided with internal screw-threads, so that they can be fastened, one to the rod E and the other to a link, F, which forms the connection between the lower spring and the yoke b . After the thimbles have been slipped over the flanges and rings the edges of said flanges are spread on the outside so as to make a tight joint. (See Fig. 1.) The inner flanges of the end springs, and also the flanges of the intermediate spring or springs, are clamped between split-rings g^* and thimbles f^* , said split-rings being provided with internal screw-threads to receive tapering screw-plugs h , formed so that, by inserting said screw-plugs in the split-rings, these rings are spread, and the flanges of the springs are firmly clamped between them and the thimbles. By these means the disk-springs are firmly connected together, and no steam is permitted to get into them, while at the same time said springs are free to expand and contract.

If steam is admitted to the steam-chest the pressure thereof has a tendency to compress the disk springs, and consequently to raise the slide-valve from its seat; and by adjusting the area of the springs in relation to the area of the back of the valve, which is exposed to the pressure of the steam, said valve can be so balanced that it will work perfectly free on its seat entirely independent of the pressure of the steam acting thereon.

If desired, the springs D may be placed in a separate compartment, as shown in Fig. 4; and in this case they will be connected to rod E by an intermediate lever, E'.

The disk-springs may be constructed of a simple diaphragm, D^* , (see Fig. 5,) which is stretched across the open end of a cup-shaped casting, D' .

What I claim as new, and desire to secure by Letters Patent, is—

1. The arrangement of the detached disk-springs D D D in combination with the slide-valve of a steam-engine, which is connected

with said disk-springs by a rod, with or without an intermediate lever, constructed and operating substantially in the manner shown and described.

2. The conical plugs *h*, split-rings *g**, and thimbles *f**, in combination with the flanges of the disk-springs, constructed and operating

substantially in the manner shown and described.

JNO. CHRISTIANSEN.
